H. G. STEEN

SLEEVE FILLER

Filed Dec. 14, 1923

Inventor
Herbert G. Steen.

Milot Steen & Co.

Attorneys.

UNITED STATES PATENT OFFICE.

HERBERT G. STEEN, OF ELMIRA, NEW YORK.

SLEEVE FILLER.

Application filed December 14, 1923. Serial No. 680,710.

To all whom it may concern:

Be it known that I, HERBERT G. STEEN, a citizen of the United States, residing at Elmira, in the county of Chemung and State 5 of New York, have invented new and useful Improvements in Sleeve Fillers, of which the following is a specification.

My present invention is a sleeve filler especially adaptable for use in connection 10 with the display of coats and other garments.

Heretofore, in arranging coats and similar garments upon forms in show windows, stores, etc., great difficulty has been experienced 15 in properly padding or stuffing the sleeves thereof so that they will assimilate the same smooth and natural appearance they present when occupied by an arm. Various means have been resorted to for the accomplishment 20 of this end, among which the employment of wads of newspaper is perhaps the most common. The great difficulty with this and analogous expedients is that it is practically impossible to distribute 25 the paper evenly so as to avoid bumps and wrinkles in the sleeve. Additionally considerable time is necessarily expended in securing even a semi-satisfactory result, and even when the task is completed there is no 30 assurance that the filling won't drop out if the sleeve is jarred or touched.

It is therefore the primary object of my invention to provide a sleeve filler which may be conveniently applied and attached 35 in a coat or other sleeve for display purposes, and one which will, when in position lend the sleeve a natural arm-occupied appearance without unseemly lumps or wrinkles.

A further object of the invention is the provision of a filler of this character which is very simple in its formation, highly efficient in use and inexpensive of manufacture.

The various features of novelty which characterize my invention are pointed out with particularity in the claims annexed to and forming a part of this specification. For a better understanding of the invention, 50 however, and of the advantages possessed by it, reference should be had to the accompanying drawings and descriptive matter in which I have illustrated and described what I now regard as the preferred embodiment 55 of my invention.

Figure 1 is a side elevation of the improved sleeve form;

Fig. 2 is a side elevation illustrating the outside piece or member of the improved sleeve form;

Fig. 3 is a side elevation illustrating the inside piece or member of the sleeve form;

Fig. 4 is a rear end elevation of the improved sleeve form;

Fig. 5 is a side elevation of a coat 65 equipped with the improved sleeve form;

Fig. 6 is a rear elevation of a coat equipped with a pair of the improved sleeve forms.

Referring specifically to the drawing, 70 wherein like reference characters have been used to indicate like parts throughout, numeral 5 denotes a section of rubberized or similar cloth which is suitably cut to conform with the normal position of an arm in a coat sleeve. This portion 5 forms the inside of the sleeve filler, the outer portion thereof comprising a section of rubberized cloth 6 of somewhat increased width and length. The side and bottom edges of the 75 section of cloth 6 are lapped over the corresponding edges of the cloth 5 and suitably vulcanized thereto to form an air tight bag which when inflated as described herein- 80 after will assume the normal position of an arm to cause the sleeve of a coat upon a display form to hang in a natural manner as it would upon a human wearer.

The rubberized fabric portion 5 at its upper end is cut out somewhat as indicated 90 at 5^b. This formation while not altogether necessary is considered desirable to permit better fitting of the filler in the sleeve, the filler at its upper end being closed by means of an armpit shield of relatively heavy rubberized fabric, this shield being denoted at 7. The armpit shield 7 will be lapped over the upper and side edges of the portions 5 and 6 and vulcanized thereto, it being understood of course that it will also be 100 vulcanized to the section 5 along the marginal upper edge thereof. This armpit shield will be so cut and so positioned that when the sleeve filler is inflated by means of the rubber tube 8 at the lower end thereof the outer and inner lines of the filler will merge with the lines of the form upon which the coat is hung and give the junction of the sleeve and shoulder a smooth natural 105 appearance.

110

As a precautionary measure the upper edge of the filler is closed by a rubberized strip 10 which is suitably vulcanized to the upper sides of the filler. As a means for 5 securing the filler in place in the sleeve, I have provided a tab 11 which is disposed and held in place by means of the strip 10. This tab 11 will be pinned to the inside of the coat just below the armpit thereof. It 10 may, if desired, be pinned to the form upon which the coat is hung.

The tube 8 may be located at the bottom edge of the filler in any preferred position and after the filler has been inflated the 15 outer portion of the tube may be closed by clamping the same with a rubber band.

From the foregoing description read in connection with the accompanying drawing, the novel features and advantages of my 20 sleeve filler will be readily appreciated by those skilled in the art. In using the appliance it is considered preferable to dispose the filler in the sleeve while in an operative condition. The filler having been 25 secured in the sleeve as above stated by means of the tab 11. It will be inflated to a sufficient degree to display the sleeve in the most effective manner. But very little time will be required for this operation and 30 when the coat is to be removed from the display form it is only necessary to let the air out of the filler after which it can be unpinned and removed.

When out of use it may be folded up and 35 occupies very little space.

Attention is especially directed to the fact that the longitudinal edge portions of the section 6 are overlapped with and are vulcanized to the edge portions of the inner 40 section 5 to provide double thicknesses at the front and rear edges of the sleeve shaper. This renders the front and rear edges of the sleeve form or shaper less expansible than the central portions of the sections 5 45 and 6 and consequently when the shaper is inflated it will be somewhat elliptical in cross-section and the rather sharp front and

rear edges of the same will be positioned in contact with the inner sides of the creased front and rear edges of the sleeve to effectively display the creases at the front and rear edges of the sleeve. 50

It is thus seen that the natural form of the coat sleeve is effectively displayed and it is not rounded at its front and rear edges as 55 would be the case without the double thickness at the front and rear edges of the sleeve shaper.

The embodiment of the invention shown and described will be considered as illustrative of what I now consider the preferred form. However I reserve the right to make various changes therein as may fairly fall 60 within the spirit and scope of the invention as claimed. 65

I claim:

1. A pneumatic sleeve shaper for coat forms comprising inner and outer expandable sections, the longitudinal edge portions of one section being extended over and vulcanized to the longitudinal edge portions of the other section whereby to provide double thickness edge portions adapted to be positioned in contact with the inner sides of the creased front and rear edge portions of the 70 75 coat sleeve to display the creases in the sleeve.

2. A pneumatic sleeve shaper for coat forms comprising inner and outer expandable sections, the longitudinal edge portions of one section being extended over and vulcanized to the longitudinal edge portions of the other section whereby to provide double thickness edge portions adapted to be positioned in contact with the inner sides 80 85 of the creased front and rear edge portions of the coat sleeve to display the creases in the sleeve, said double thickness front and rear edge portions being less expansive than the central single thickness portions of the 90 sections.

In testimony whereof I affix my signature.

HERBERT G. STEEN.
